CLAIM

The ornamental design for sunglasses, as shown and described.

DESCRIPTION

FIG. 1 is a perspective view taken from the front, top and left side of the sunglasses, showing my new design;

FIG. 2 is a perspective view taken from the rear, top and right side of the sunglasses;

FIG. 3 is a front elevational view of the sunglasses;

FIG. 4 is a rear elevational view thereof;

FIG. 5 is a top plan view thereof;

FIG. 6 is a bottom plan view thereof;

FIG. 7 is a right side elevational view thereof, the left side elevational view being a mirror image of the right side elevational view; and,

FIG. 8 is a perspective view taken from the top, rear and left side of the sunglasses with the light-shielding covers slid back and temples folded.
